UNITED STATES PATENT OFFICE.

OSCAR JACKSON, OF DANVILLE, ILLINOIS.

PROPPED LADDER.

1,284,690.

Specification of Letters Patent. Patented Nov. 12, 1918.

Application filed February 12, 1917. Serial No. 148,067.

To all whom it may concern:

Be it known that I, OSCAR JACKSON, a citizen of the United States, and resident of Danville, in the county of Vermilion and 5 State of Illinois, have invented certain new and useful Improvements in Propped Ladders, of which the following is a specification.

This invention relates to ladders and has 10 more particular reference to an improved collapsible ladder.

The invention has for its principal object to provide a ladder so constructed as to permit the folding of the same into compact 15 form, thus, facilitating the carrying of the same and allowing the setting up thereof in operative position with but little effort; producing a ladder capable of withstanding severe strain and weight.

20 It is a more specific object of the invention to provide novel means for joining the stiles and rungs of the ladder construction in a manner such as will prevent relative movement of the same in a way to allow collapsing or sagging or weakening of the said ladder construction.

Another important characteristic of the 30 invention resides in the novel mounting of the various ladder rungs so that the same may be swung into folded positions upon the collapsing of the ladder and also, that the same will properly adjust themselves with relation to the ladder stiles when in operative positions to render the same firm 35 and solid.

Among other aims and objects of the invention may be recited, the provision of a ladder of the character mentioned with a view to compactness, and in which the number of parts are few, the construction simple, the cost of production small, and efficiency of operation high.

In order that the invention and its manner of application may be readily understood by those skilled in the art, I have in 45 the accompanying illustrative drawings and in the detailed following description based thereon set forth the preferred embodiments of the invention.

50 In these drawings:

Figure 1 is a perspective of my improved ladder;

Fig. 2 is a fragmentary detail in elevation showing the mounting of one of the foldable 55 rungs or steps thereof and the engagement

of the top bracing elements with certain of the stiles;

Fig. 3 is a fragmentary longitudinal section through a portion of the ladder;

Fig. 4 is a horizontal section through the 60 stiles thereof showing the arrangement of the rungs upon the same and the method of bracing the said rungs;

Fig. 5 is a detail in perspective of one of the ladder steps; 65

Fig. 6 is a detail in perspective of the manner of securing certain of the stile bracing elements to the channeled rung receiving members arranged thereon; and

Fig. 7 is a fragmentary detail in elevation 70 of a slightly modified form of mounting for the ladder rungs.

Having more particular reference to the drawings wherein like reference characters designate corresponding parts throughout 75 the several views thereof, the improved ladder construction may be stated to include pairs of spaced apart parallel arranged stile members 1 and 2, the inner or adjacent faces of which have secured thereto by rivets or 80 other like fastening devices, channeled members 3 and 4, it being noted that the said channeled members extend throughout the entire length of the stiles 1 and 2 and have the ends thereof so formed as to lie flush 85 with the respective ends of the said stiles.

Prop elements 5 are hingedly secured to the upper ends of each of the stiles 1 and 2 by hinges 6 and have pivotally engaged with the same intermediate their ends sectional 90 arms 7, the remaining extremities of the arms extending into pivotal engagement with the adjacent stiles 1 and 2 as at 8 and having their adjoining ends similarly connected to permit folding or collapsing thereof when it is desired to move the props 5 to 95 positions in proximity of their respective stile members. To maintain the sections of the arms 7 in horizontally alined positions when the props 5 are swung into operative 100 positions, hooks 9 are formed upon certain of the ends of the said sections and are adapted to engage with portions of the adjoining sections as shown in Fig. 1. By so connecting and bracing the sectional arms 7, 105 it will be appreciated that the collapsing of the props 5 will be prevented when they are once moved into operative or set up positions.

A longitudinally disposed bracing arm 10 is pivotally engaged with a suitable 110

apertured lug as carried upon one of the props 5 as at 11 and has its remaining or free extremity notched whereby the same may be swung into engagement with a corresponding notch as formed in that section or arm 7 as opposite the mounting of the same. Hence, undue relative movement of the proping element 5, whereby to permit sagging or possible collapsing of the ladder construction will be eliminated.

A plurality of rungs or steps generally indicated by the numeral 12 is provided and have their opposite extremities reduced as at 13 and 13', the said reduced extremities 15 being adapted to be received within the channelled members 3 and 4 as affixed to the inner or adjacent faces of the stiles 1 and 2. To the under side or faces of each of the rungs 12, metal straps 14 are secured 20 through the medium of rivets 15 or other like fastening devices, the said straps being of a length slightly greater than their respective rungs to permit the rolling of certain of the ends thereof upon themselves to 25 provide eyes 16 and further to permit the forming of right-angularly disposed curved lip portions 17 upon the remaining ends thereof. A plurality of pivot bolts 18 are passed transversely of the channelled members 30 3, suitable openings being formed in the sides of the said channel members, some of which are elongated to provide slots 19, which by their length will allow slight movement of the said pivot bolts therein. The 35 pivot bolts 18 are passed through the eyes 16 formed upon certain of the ends of the metal straps 14 and are secured in position with respect to their respective channel member by suitable fastening devices. 40 Other bolts 20 are passed through the side portions of the channelled member 3 as arranged upon the opposite stile 2 at points in exact horizontal alinement with the arrangement of the pivot bolts 18 in the channel member 4. As will be noted, the bolts 20 are so arranged with relation to the rear or base wall of the channelled member 3 as to be in spaced relation therefrom and as a consequence, will permit the passage of the 45 curved lip portions therebetween, that is, those lip portions 17 formed upon the remaining extremities of the metal straps 14 affixed to the various ladder rungs 12. Due to the slight inherent resiliency of the lips 50 17, the same will, by reason of the curved portions therein be caused to snap over the various bolts 20 when their respective rungs 12 are swung into operative or set up position, thus, preventing accidental removal of 55 the same. With the engaging of the lip portion 17 with the bolts 20, the various runs 12 will be permitted to move slightly, yet sufficiently to allow those portions of the metal straps 14 directly over the bolts 60 65 20 to firmly seat thereon. The lip por-

tions 17, will also by reason of the adjusting movement of the rungs 12 be caused to fully engage their respective bolts 20, since those portions of the rungs arranged thereover will rest directly upon the said bolts.

To prevent relative movement of the stiles 1 and 2 when the ladder is set up, bracing bars 21 are pivotally engaged with the rear marginal edges of the channelled members as at 22 and are extended diagonally into engagement with the lower extremities of the opposite channelled members, whereat, the opposite ends thereof are passed over suitable screw threaded studs 23 carried upon the adjacent side portions of the channelled members 3 and 4, the said studs having suitable locking nuts turned into engagement with the threaded portions thereof, thereby securely positioning the remaining extremities of the brace bars 21 and efficiently bracing the stiles 1 and 2 in their spaced apart positions.

As a means for further bracing the stiles 1 and 2, a top member 24 is hingedly secured to the upper extremity of the stile 2 through the medium of an ordinary hinge 25 pivotally secured to the said stile 2 at 26 while upon the remaining or free extremity of the same a depending flange 27 is secured, the flange being adapted to snugly engage the outer face of the stile 1 when the top member is swung into horizontal or operative position. When the top member 24 is in inoperative position, the same will be permitted to lie adjacent the outer face 100 of the stile 2 by means of its hinged connection therewith. To permit carrying of the ladder construction when the same is in folded position, a handle 28 may be and preferably is secured to one of the stiles, thus enabling the user to readily grasp the collapsed or folded construction.

To collapse my improved ladder, the various rungs 12 are swung upwardly upon the pivot bolts 18 to cause disengagement of the lip portions 17 with the various bolts 20 as arranged upon the stiles 2 and the diagonally disposed brace bars 21 are disengaged from the several screw threaded studs 23 by removing the locking nut therefrom. The top member is now swung out of engagement with the stile 1 into a position adjacent the outer face of the stile 3 and the prop members 5 are folded into their inoperative positions by breaking the jointure of the sectional arms 7 and disengaging the longitudinal arm 10 from the notched portions formed in certain of the said sectional arms 7. With the various parts thus disassembled, they may be readily placed in compact form and a suitable binder or tie placed thereabout to permit the construction to be readily carried by means of the handle member 28.

It is of course to be understood that the

invention is not limited to the specific mounting of the rungs 12 of the ladder construction upon the several stiles thereof but may be varied within the spirit of the invention 5 such as conditions or preference may dictate. To this end, I have shown in Fig. 7 a slightly modified form of mounting of the ladder rungs 12, wherein instead of providing a plurality of continuous channeled members 3 and 4 as shown in the preferred embodiment of the invention, substantially U-shaped brackets or studs 29 are secured to the inner or adjacent faces of the said stiles 2 at spaced apart intervals throughout the 10 length thereof. Suitable openings are formed in the sides of the brackets to permit the insertion of pivot bolts and stop bolts therethrough, those brackets receiving the pivot bolts 18 being provided with slots 15 in certain of the sides thereof to permit slight movement of the same for an obvious purpose. 20

I also desire to have it understood, that my novel form of rung mounting may be 25 fully as well used in conjunction with various types of ladders other than that particular type herein shown and that the same may not only be used in conjunction with the collapsible type of ladder but also in conjunction 30 with the rigid type of ladder.

As hereinbefore indicated, I do not wish to be understood as confining the invention to the particular embodiments chosen for illustration herein nor to the exact construc-

tion, arrangement and adaptation of the 35 parts shown and described, but I reserve the right to make any changes and alterations that fairly fall within the spirit and scope of the invention.

I claim:

1. A propped ladder including channeled side members, spaced steps pivoted to one of said side members and having their free ends reduced and received by the remaining side member, spaced stops on said remaining side member for supporting the free ends of the steps, and bracing bars pivoted to portions of the side members and having the free end thereof adapted for engagement with the opposite side members. 40

2. A propped ladder including channeled side members, spaced steps loosely pivoted to one of said side members and having their free ends reduced and provided with angularly disposed engaging means, spaced stops on the remaining side member for receiving and supporting the free ends of said steps, bracing bars pivoted to portions of said side members and having their free ends adapted for detachable engagement with the opposite side members, and a prop bracing member hinged to one end of one side member having its free end hooked and adapted for engagement with the adjacent end of the remaining side member. 45

In testimony whereof, I affix my signature hereto.

OSCAR JACKSON.
